MEANS FOR CONTROLLING FLOW OF ELECTROLYTE TO AN ELECTROLYTIC CELL

Julian M. Sturtevant, Branford, Conn., assignor to the United States of America as represented by the United States Atomic Energy Commission

Application November 7, 1946, Serial No. 708,426

5 Claims. (Cl. 204—194)

1

This invention relates broadly to a method and apparatus for automatically titrating a fluid, mainly for maintaining constant the position of a liquid-liquid boundary formed by superimposed fluids. More specifically the present invention relates to an improved method and apparatus for controlling the feed of a liquid electrolyte in an electrolytic isotope separating apparatus of the type described and claimed in the copending application of Samuel L. Madorsky et al., 10 U. S. N. 432,185, filed February 2, 1942, now U. S. Patent No. 2,645,610, issued July 14, 1953.

In the method of electrolytic isotope separation as described in the above identified copending application the electrolytic or reaction bath comprises a solution of a salt of a metal the isotopes of which are to be separated. This salt solution is situated in an electrolysis cell or chamber provided with a permeable barrier positioned between the electrodes. To effect a separation of the isotopes of the desired material a voltage is applied between the electrodes, thereby imparting velocities to the cations in accordance with their respective masses. An opposite drift or counterflow is imparted to the entire solution by slowly titrating an electrolyte at the cathode end of the cell. If the rate of feed of this electrolyte is properly adjusted with respect to the current and cation drift only the lighter or faster moving cations will reach the vicinity of the cathode.

The present invention is directed to a method and apparatus for automatically maintaining the feed of this electrolyte, to effectively retard the less mobile cations and thereby insure proper operation of the separator.

In operation of such electrolysis cells, a liquid-liquid boundary has been observed (due to the different indices of refraction of the two liquids) between the electrolyte and the salt solution of the desired material (the position of this boundary being dependent upon the acid concentration of the electrolyte adjacent to the cathode). As the electrolysis proceeds the motion of the ions in the electric field causes this boundary to move. For proper operation the liquid electrolyte should be added so as to maintain this boundary stationary.

The operation of my improved method and apparatus for controlling the feed of this electrolyte is predicated on the observation that the electrical conductivity of the electrolyte changes rapidly at the boundary (the conductance of the acid electrolyte being greater than the conductance of the salt solution); and upon my discovery that

2

the temperature of the poorly electrically conducting solution is higher than the more readily electrically conducting solution as a result of the flow of the electrolysis current. Coincident with this discovery I hit upon the idea of utilizing this temperature difference in the two liquids as a means for controlling the titration or feed of the simple liquid electrolyte to maintain the boundary layer substantially stationary throughout the operation of the electrolysis cell. It occurred to me that a resistance unit inserted in the cell solution with the boundary located at its midsection for example, would have a temperature that would vary with any change in the location of the boundary layer; and that this change in temperature would alter the electrical resistance of this unit. Accordingly I set out to devise a system for controlling rate of feed of the liquid electrolyte that would be responsive to changes in the boundary position whereby the rate of feed would be adjusted automatically to maintain a predetermined acid concentration at the cathode thereby keeping the boundary fixed in position.

25 In a preferred embodiment of this invention I utilized an extremely fine enameled copper wire encased in a Pyrex tube as the resistance unit; and inserted this resistor in the electrolytic solution adjacent to the cathode with the boundary layer at its midsection. This resistor, which is preferably bifilarly wound, is connected to form one of the arms of a balanced Wheatstone bridge. Thus any change in the average temperature of this resistance unit will produce a change in its average resistance thereby unbalancing the bridge and producing an output voltage that may be amplified and utilized as a control for the feed of the liquid electrolyte. Accordingly it is apparent that I may utilize the change in average 35 temperature concomitant with the movement of boundary layer of the salt solution and liquid acid electrolyte for controlling the feed of acid in a manner to counteract the aforesaid movement of the boundary.

40 45 I prefer to utilize the amplified output from the bridge network to heat a bi-metallic strip upon which is supported a levelling cup containing the said liquid electrolyte at a constant predetermined level therein; and to utilize a flexible conduit to permit the flow of liquid from the cup into the reaction chamber or electrolysis cell. With this arrangement the pressure head of the liquid electrolyte in the cup is altered through 50 the flexing of the bimetallic strip to control the

feed or titration of this fluid liquid electrolyte into the reaction bath or electrolysis cell.

In view of the foregoing an apparent object of this invention is to provide an automatic system for titrating a fluid.

A further and more specific object of this invention is to provide a method of automatically titrating a fluid to maintain constant a liquid-liquid boundary layer between fluids of different electrical conductivity.

Still another object of this invention is to utilize the change in average temperature with movement of a boundary layer of two liquids of different temperature as a means for controlling the feed of one of said liquids in a manner to counteract the aforesaid movement of said boundary.

A more limited and specific object of this invention is to provide an improved method for controlling the counterflow in an electrolytic system for the separation of isotopes to the end that the less mobile ions will be effectively retarded and the more mobile ions permitted to reach the cathode region. Such automatic control of drift or counterflow makes it possible for one attendant to supervise the operation of a large number of separators; but what is more important such automatic control improves the efficiency of the isotope separating system.

In the drawings:

Fig. 1 is a diagrammatic view partly in cross section of an electrolytic system for separation of isotopes in which my invention has particular application; and Fig. 2 is a schematic illustration of the apparatus employed in practicing the invention.

As is shown in Fig. 1 an apparatus for the separation of isotopes of a substance may include a U-shaped glass tube 10, provided at one end with an enlarged cup-shaped portion 11 into which an anode 12 is inserted. A spillway 13 is formed in the wall of the tube at the anode region 14. Similarly, the other end of the U-shaped tube 10 is enlarged to provide a cup-shaped cathode region 14 into which the cathode 17 is inserted. Disposed in the tube 10 in the bottom of the U-shaped portion, for example, and intermediate between the cathode and the anode, is a permeable plug 16 of alundum or the like. A glass tube 18 is connected into the U-shaped tube 10 at the cathode region 14 to provide a branch arm thereof.

It will be understood that the apparatus may be used for the separation of isotopes of any metal of which the ionized isotopes possess different mobility. By way of example uranium has isotopes U^{235} and U^{238} , the ion of U^{235} being more mobile in an electrolyte than the ion of U^{238} .

In carrying out the separation of U^{235} and U^{238} a solution of UO_2Cl_2 may be fed into the glass tube 10 at a predetermined rate by means of the feed tube 30 positioned at the anode end thereof. The fluid in excess of the required quantity flows out of the tube 10 by means of the spillway 13. An HCl solution is added in controlled amounts at the cathode end of the tube 10 in a manner fully explained below.

The function of the alundum plug 16 is to minimize remixing by turbulence and convection. The plug permits the flow of ions but also quiets the flow through the separating zone. The lighter U^{235} ions, of higher mobility, would tend to accumulate around the cathode at a faster rate than the less mobile isotope ions, i. e., those of the heavier U^{238} ; but if no further steps are

taken and time is allowed to elapse, both isotopes will eventually gather at the cathode 17. However, by adding a liquid electrolyte at the cathode to maintain a sufficient number of ions (other than uranium ions) to insure the desired electrolytic flow of current between the working electrodes, the resulting flow of liquid will oppose the electrolytic migration of uranium ions towards the cathode; and if the rate of flow of the added electrolyte is appropriately balanced against uranium ion migration the uranium ions can be, in effect, selectively retarded in an inverse relation to their mobilities. Thus in a system of the type shown, by the addition of HCl (i. e., an aqueous solution of hydrochloric acid) at the cathode region at a carefully determined rate, the heavy U^{238} ions will tend to be swept back more than the lighter and more mobile U^{235} ions or rather the latter ions will be more able to overcome the counterflow and will progress further toward the cathode 17. Under presently preferred conditions, the flow is adjusted so that few, if any, of the uranium ions actually reach the cathode, and a so-called boundary layer between the HCl and UO_2Cl_2 solutions is thus formed (provided the addition of HCl is at the proper rate) at a position in the system between the cathode and the plug 16, e. g., as indicated by the reference numeral 20. Under proper conditions this boundary layer can actually be seen because of the difference in index of refraction of the two solutions. The U^{235} ions tend to migrate to the region of this boundary while the counterflow retards the U^{238} ions to a greater extent so that a gradient of the relative concentration of U^{235} to U^{238} ions can be established between the boundary and the anode region.

But for the continued addition of HCl at the cathode region the boundary would move toward the cathode and consequently the boundary of the general type herein described has sometimes been referred to as a "moving boundary." In carrying out the present invention the boundary is preferably restrained from so moving by automatically adjusting the feed of the acid electrolyte into the system at the cathode region. It will now be seen that as the system continues to operate, a separation or enrichment of the isotope U^{235} is established and maintained at a zone just below the boundary; and by appropriate means such as the petcock 19 a solution of the uranium salt enriched as to its U^{235} isotope content and generally impoverished as to its U^{238} content can be withdrawn continuously or intermittently from this zone.

The apparatus embodying the present invention is designed to maintain stationary the boundary between the solutions of UO_2Cl_2 and HCl.

The apparatus illustrated in its preferred embodiment consists of a resistance thermometer 21 immersed in an electrolytic bath with the boundary 20 located at its midpoint. The thermometer comprises in this embodiment of the invention a resistance element and may consist of a coil 22 bifilarly wound and contained in a Pyrex tube 23. In one specific embodiment of the invention the resistance unit comprised an extremely fine enameled copper wire, and coils of this unit about 2 cm. long and 3 mm. in diameter are contained within a Pyrex tube of about 6 mm. in outside diameter. The resistance of this unit at the operating temperature of 6.5°C. is 200 ohms. This resistance unit is connected preferably into an arm of an alternating current Wheatstone bridge 24. The bridge

is brought to balance with the boundary layer at the midsection of the coil 22 so that any change in the position of the boundary layer will change the average temperature of the thermal resistance unit thereby unbalancing the bridge. For example, a rise in the boundary layer increases the average temperature of the resistance unit increasing the ohmic resistance of the coil 22 connected to form one arm of the bridge thereby unbalancing the bridge. The output of the bridge 24 is applied to the grid of the electron tube 25 which comprises the first stage of the two stage amplifier illustrated in Fig. 2. The output from the tube 25 is applied for further amplification as an input signal to the grid of the electron tube 26 and is there combined with an adjustable voltage component which is 90° out of phase with the line voltage. This adjustable out-of-phase voltage component is obtained across the resistor 27 and is made variable as to its magnitude by means of the adjustable tap indicated at 28. The output of the amplifier circuit, the phase of which varies with the degree of off balance of the bridge, is used to give a continuous control of the plate current of the thyratron tube 29.

The use of the bridge controlled thyratron for temperature regulation is well known in the art and the particular circuit illustrated in Fig. 2 was patterned after a circuit devised by D. Bancroft and described in Review of Scientific Instruments, vol 13, pages 24 and 114 (1942). Accordingly, further description is omitted in the interest of clarity.

As shown in Fig. 2 the load for the plate circuit of the thyratron tube 29 comprises the heating coil 32 of the bimetallic strip 31. As a specific example the heating coil 32 may comprise a 500 ohm constantan or nichrome wire for use with a 2050 thyratron capable of passing a maximum of 100 milliamperes. The bimetallic strip 31 is fastened at one end to a support of adjustable height and supports at its free end a leveling cup 33 provided with an overflow 34. A flexible conduit 35, rubber tubing for example, communicates the liquid level of the cup 33 with a branch arm 18 of the U-shaped tube 10 (which comprises the electrolytic cell). On being heated by the coil 32 the strip 31 will flex altering the height of the liquid level in the cup to change the feed of acid electrolyte into the branch arm 18 and into the tube 10 comprising the electrolysis cell. It is preferred to utilize a bimetallic strip that will give a total throw in response to maximum current, through its heating coil, of at least 1 cm. A predetermined and constant level of the liquid electrolyte in the cup is maintained by the feed line 36 and the overflow 34.

It may be preferred to utilize two thermal resistance elements and to connect each of these elements in opposite arms of the Wheatstone circuit for the purpose of doubling the sensitivity of the apparatus. For example, both of the resistance elements may be supported in the same Pyrex tube, each positioned in the cell with the boundary layer in the mid section of the thermal element.

It is observed that the resistance elements will respond to changes due to causes other than movement of the boundary. By locating a separate resistor in the thermometer tube, in a position above the boundary, compensation may be made for changes in the temperature of the reaction bath. Another method for compensating for changes in temperature is to utilize two sepa-

rate resistance units, one mounted above and the other below the main thermionic resistance unit that is positioned at the boundary. In this way partial compensation is obtained for temperature changes resulting from variations in the electrolysis current.

It will be understood that the apparatus described may be used to effect separation of isotopes of any metal wherein the isotopes are sufficiently different in mass to permit their segregation by the counterflows disclosed above. Furthermore, it will be obvious to those skilled in the art that electrolytes other than the ones described may be used in the separation of the particular uranium isotopes. In its broad aspect this invention involves controlling the boundary between juxtaposed solutions in an electrolytic system in response to changes in the average temperature of an element positioned within the electrolytic system in the region of said boundary. Accordingly, it is understood that other types of circuits could be employed for the same purpose, and that the particular circuit shown in detail herein is but one example of the many different ways in which the invention may be practiced.

I claim:

1. In a system including an electrically conducting fluid superimposed upon a fluid of a different electrical conductivity, to form a boundary therebetween, means for causing an electrolysis current to flow in said fluids to heat said fluids to a temperature inversely related to their respective conductivities, an electrical resistance unit 30 the resistance of which varies with temperature bathed in said fluids in the region of the boundary between said fluids, a container for an additional supply of one of said fluids and means responsive to the changes in the electrical resistance of 35 said unit, for controlling the flow of fluid from said container to said system.
2. In an electrolytic system having superimposed fluids of different temperatures forming a boundary therebetween apparatus for maintaining the position of the boundary which comprises a container for the additional supply of one of said fluids, a resistance unit the resistance of which varies with temperature bathed in said fluids in the region of said boundary, having an 40 average temperature responsive to the position of said boundary, a bridge circuit including as one leg thereof the resistance of said unit and means responsive to the change in the balance of said bridge circuit resulting from the movement of said boundary relative to said unit for controlling the addition into said system of said fluid within said container.
3. In the art of titrating a liquid into a chamber containing a reaction bath, the combination 45 comprising a chamber for said reaction bath, a leveling cup containing a supply of said liquid at a constant predetermined level therein, a bimetallic strip for supporting said cup, a control circuit responsive to changes in the electrical characteristics of said bath for heating said bimetallic strip to cause said strip to flex thereby altering the level of said cup and a flexible conduit communicating said cup and said chamber.
4. In an electrolytic system a cell containing a 50 plurality of juxtaposed fluids of different electrical conductivity forming a boundary therebetween, and having electrodes disposed in said fluids on opposite sides of said boundary, for passing a predetermined electric current there-through; means for controlling the position of

said boundary comprising a resistance element the resistance of which varies with temperature bathed in said fluids in the region of said boundary so that its average temperature varies with the position of said boundary, a supply vessel containing one of said fluids at a predetermined level therein, and means responsive to the changes in the average temperature of said resistance unit for altering the position of said supply vessel relative to said cell for regulating the admission into said system of the fluid contained therein.

5. In a system for the electrolytic separation of isotopes of a substance wherein the less mobile ions of a heavy isotope are swept back from the cathode by a counterflow of fluid which permits passage of the more mobile ions of a lighter isotope, apparatus for controlling the rate of counterflow which comprises a resistance unit the

5
10

resistance of which varies with temperature bathed in said electrolyte having an average temperature responsive to changes in said counterflow and means responsive to the changes in resistivity of said unit for regulating the addition of an electrolyte to said fluid to regulate the counterflow to maintain said unit at a predetermined temperature.
